UNITED STATES PATENT OFFICE.

WILLIS J. SMITH, OF ST. OLAF, IOWA, ASSIGNOR OF ONE-HALF TO J. J. TAYEK, OF FROELICH, IOWA.

COMBINED RAIL BRACE AND TIE.

1,212,827.

Specification of Letters Patent. Patented Jan. 16, 1917.

Application filed January 4, 1916. Serial No. 70,188.

To all whom it may concern:

Be it known that I, WILLIS J. SMITH, a citizen of the United States, residing at St. Olaf, in the county of Clayton and State of Iowa, have invented certain new and useful 5 Improvements in Combined Rail Braces and Ties; and I do hereby declare the following to be a full, clear, and exact description of the invention, such as will enable others 10 skilled in the art to which it appertains to make and use the same.

The object of this invention is to improve the construction of a combined rail brace and tie by providing a device of this nature 15 that will positively hold the rails from spreading apart, and of such construction that it can be manufactured cheaply and will be durable and efficient in operation.

Other objects will appear and be better 20 understood from that embodiment of my invention of which the following is a specification, reference being had to the accompanying drawing, forming a part thereof, in which:

25 Figure 1 is a sectional plan view of a railway track, and showing the combined rail brace and tie applied to the rails, Fig. 2 is a transverse section taken through the track shown in Fig. 1, Fig. 3 is a plan view of one 30 of the rails of the track, and one of the track ties therefor and showing the invention applied thereto, Fig. 4 is a bottom plan view of the rail tie plate, and Fig. 5 is a side elevation of the tie rod, and showing the 35 same removed from operative position.

Referring to the drawing more in detail, the numeral 1 designates a pair of tie plates arranged respectively at the opposite ends 40 of a railway tie, designated 2, and adapted to form seats for the companion rails 3 of the track. Each plate has its ends projecting beyond the respective inner and outer longitudinal edges of the adjacent rails and is provided at its end with a plurality of 45 spike openings, preferably three in number, certain of the openings being opposed and spaced, as shown at 4 and 5, and the other opening being located in line with the space between the first-mentioned openings and 50 near the adjacent terminal of the plate. The under side of each plate 1 is provided with a plurality of diagonally extending and intersecting ridges or ribs 7, the said ridges or ribs being sharpened so as to penetrate

the upper surface of the tie 2, and help to 55 prevent movement of the plate 1.

Associated with the plates 1 is a pair of rail brace blocks 8, which are located on the outer longitudinal side of the rail, and each is provided with a substantially triangular 60 shaped base flange 9, the said flange having openings therein registering with the openings formed in the adjacent outer end of the plate 1, for the reception of spikes 10, which extend through the base flange 9 and the 65 plate 1 and have their shanks embedded in the tie 2, as shown in Fig. 2 of the drawing. The openings 4 and 5, which are located at the inner end of the plate 1, receive spikes 11, which have their heads engaging the base 70 flange of the adjacent rail 3 and their shanks extending through the plate 1 and embedded in the tie 2.

A tie rod 12 is located between the companion rails 3 and disposed above the upper 75 side of the tie 2, and has its opposite ends bent downwardly and inserted through the extreme openings 6 at the inner ends of the plates 1 and are embedded in the rail tie 2, as shown in Fig. 2 of the drawing. Each 80 of the bent terminals of the tie rod 12 is provided with a plurality of locking shoulders 13, which are adapted to prevent accidental disconnection of the tie rod from operative position.

The device described in the foregoing, is adapted to be associated with the rails at track curves and will positively prevent the rails from spreading at the curves.

Having thus described my invention what 90 I claim as new, is:

The combination with a rail tie, of a pair of tie plates positioned, respectively, at the opposite ends of the tie and each having each of the opposite ends thereof provided 95 with a pair of opposed openings, and another opening alining with the space between the adjacent pair and located adjacent the terminal of the end of the plates, the said plates being adapted to engage beneath the companion rails of a track and having their under sides provided with intersecting ribs for engaging in the tie, rail braces mounted on the outer ends of the plates and each including a substantially 100 triangular shaped base portion having its large end adapted to engage over the longitudinal edge of the base flange of a rail, a 105

rail-engaging portion projecting upward from the base portion, the said base portion of the rail brace being provided with a pair of openings located, respectively, on opposite sides of the rail-engaging portion, and also having another opening located adjacent the apex end thereof, and at a point in advance of the rail-engaging portion, the said openings in the base portion of the rail brace registering with the adjacent openings in the outer end of the tie plate, fastening elements extending through the registering openings, a tie rod extending between the

opposed plates and having its outer ends bent downwardly and extended through the 15 openings in the terminals of the inner ends of the plates and engaging in the tie, and rail-engaging elements extending through the pairs of opposed openings at the inner ends of the plates and engaging in the tie. 20

In testimony whereof I affix my signature in presence of two witnesses.

WILLIS J. SMITH.
